UNITED STATES PATENT OFFICE

GEORGE A. PERRY, OF SPRINGFIELD, VERMONT, ASSIGNOR TO JONES & LAMSON MACHINE COMPANY, OF SPRINGFIELD, VERMONT, A CORPORATION OF VERMONT

TAPER TURNER

Application filed December 21, 1928. Serial No. 327,566.

It is sometimes desired to turn a taper from rough stock, and in order that springing of the work under pressure of the tool may be minimized, it is desirable and often necessary to support the work substantially opposite to the tool. As the unturned work is rough, however, this supporting must be done back of the line of cut, where the work has been turned and smoothed by the tool, but as this smooth surface is tapering, the support must be controlled to move relative to the axis of the work to follow the taper as the tool and support are moved axially of the work.

There are times, however, when it is desirable to turn the taper after the work has first been turned cylindrical. The support may then precede the tool axially, being guided by the cylindrical part of the work and being fixed in its distance from the work axis.

This invention has for one object, therefore, to produce a taper turner in which either method of supporting the work may be used as desired, the support preceding the tool and being held at a fixed distance from the work axis when turned cylindrical work is being turned taper, and following the tool on the tapered part of the work and moving relative to the axis of the work as it is moved longitudinally thereof to follow the taper when rough work is being turned taper. To this end the support for the work, which preferably comprises a pair of work engaging elements angularly spaced about the work axis substantially opposite to the tool is so constructed that the work engaging elements may selectively be so controlled as to be moved relative to the work axis in accordance with the taper as they are moved axially, or to be held at a fixed distance from the axis, and the tool is so arranged relatively to these engaging elements that it precedes or follows these elements in axial movement in accordance with the element control selected.

Further objects and advantageous constructions will more fully appear from a more complete description of an embodiment thereof illustrated in the accompanying drawings in which

Figure 1 is an end elevation of the mechanism, the taper controlling cam and the work

being shown in section, the tool and work supporting element being retracted.

Figure 1a is a detail section on line 1a—1a of Figure 1.

Figure 2 is a top plan of the same mechanism.

Figure 3 is a vertical section on line 3—3 of Figure 2 showing the parts adjusted for taper guiding engagement.

Figure 4 is a fragmentary view similar to a portion of Figure 3 but with the parts adjusted to cylindrical guiding engagement, the tool being retracted.

Figure 5 is a rear elevation of the mechanism.

Figure 6 is a horizontal section on line 6—6 of Figure 3, the tool slide spring being omitted.

Figures 7 and 8 are fragmentary views partly in section showing relative positions of one of the work guiding elements and the tool for taper and cylindrical work-guiding, respectively.

Figures 9 and 10 are detail perspectives of certain parts of the mechanism.

Figure 11 is a section on the plane of lines 11—11 of Figure 9.

Figure 12 is a section similar to a portion of Figure 6, but showing the parts adjusted for cylindrical work guiding.

Referring to these drawings, at 1 is indicated a traversing member for carrying a tool 2 and the work supports, which, as shown, comprise a pair of rolls 3 and 4. This traversing member is mounted on the lathe or other machine in place of or fixed to the usual traversing tool carriage so that it may be traversed axially of the work which is shown at 5. A cam bar as at 6 is employed to control the pattern of the taper to which the tool shall cut the work, this cam as shown being fixed to the machine frame as by means of the bolt 7 (see Figure 5) and extending lengthwise of the work which is to be turned.

The member 1 comprises a base portion 10 carrying a laterally movable slide 11 which is provided with a tool holding portion 13 to which may be fixed the tool 2 as by means of the securing and adjusting screws 14.

The upper portion of this slide member 11

is shown as perforated for the slidable reception of a threaded shank portion 15 of a cam follower bar 16 having a follower portion 17 engageable with the outer edge of the cam bar 6. This follower portion is held against the cam as by a leaf spring 170 having its upper end bearing against the end of the slide 11 adjacent to the follower portion, and having its lower end fixed to the member 10 as by the screw 171. The opposite edge of this cam bar slidably engages a portion 18 of the member 1. This cam follower bar 16 is shown as having threaded on its outer end beyond the slide 11, and against which the slide is pressed by the spring 170, a nut 19 having a series of holes 20 in its periphery within which may be extended a rod to serve as a handle for turning this nut. As shown in Figure 1a this nut 19 has a long hub portion 21 on which is mounted a sleeve 22 having a split portion as at 23 provided with a clamping screw 24 by which the sleeve 22 may be clamped to the hub 21 so that by turning the sleeve 22 the nut 19 will also be turned. The sleeve 22 is provided at its outer end with a handle portion 25. Adjacent to its inner end this sleeve 22 is provided with an outwardly extending pin 26 which may be engaged with a pin 27 projecting outwardly from the member 11. This construction forms an adjustable connection between the cam follower bar 16 and the tool slide 11 so that the position of the tool 2 may be adjusted as desired and when once adjusted may be re-set with exactness. This may be done by loosening the sleeve 22 from the nut, bringing the cam follower 17 up against the cam and the tool carried by the tool slide up to the face of a standard piece of turned work and then screwing the nut 19 until it contacts with the face of the tool slide 11. The sleeve 22 is then adjusted until the pin 26 makes contact with the pin 27 and is secured in position by the clamp bolt 24 to the nut. The nut may then be turned backwardly to loosen the cam follower bar 16 whenever desired and when it is thereafter desired to set the tool to the proper position, it is only necessary to tighten the nut by turning the sleeve 22 until the pin 26 contacts with the pin 27. One face of the pin 26 may be cut away in order that on the next complete revolution of the nut in a direction to loosen the cam follower bar it may clear the outer end of the pin 27 so that it may be turned in the loosening direction more than a single turn when desired.

The member 1 in its cover plate 80 is provided with a slideway 30 out of the plane of the main portion of the slide 11 but within which may ride a vertical slide 31 carrying on a suitable journal 32 at its lower end the work-engaging roll 4. As shown best in Figures 9 and 11 this slide 31 has a wedge block 34 on its rear face with which may be engaged the inclined face 35 of a wedge element

36. This wedge element 36 is slidable in a horizontal slot 40 in the slide 11 and its outer end may be engaged by an adjusting abutment screw 41 threaded at its outer portion through a portion 42 of the slide 11. As the slide 11 is moved laterally to feed the tool toward the axis of the work, the inclined face 35 of the wedge element 36 acting on the wedge portion 34 of the slide 31, forces this slide downwardly so as to cause a corresponding movement toward the work axis but in a direction substantially at right angles to that of the tool toward the work axis. The slide 31 is caused to be retracted when the tool is retracted, which relieves the pressure of the wedge element 36 on the block 34, as by means of a spring 50 engaging at its lower end with a pin 51 fixed in an opening 52 in the slide member 31. The upper end of this spring engages a short bar 53, the ends of which ride in a counterbored portion 54 at the upper end of a sleeve 55 threaded through a cover plate 56 which is fixed as by means of a cap screw 57 to the upper edge of the member 1. The sleeve may thus be turned without twisting the spring.

A second work supporting slide carrying the work engaging roll element 3 is mounted in the member 1, this being shown at 60. This slide as shown is mounted horizontally substantially opposite to the stool 2 in a groove in the portion 10. It is normally urged away from the work axis as by means of the plunger 61 pressed outwardly by the spring 62 riding therein and engaging at its inner end against the base 63 of a hole 64 within which the plunger 61 is slidable. The outer end of this plunger engages a down-turned portion 65 at the outer end of the slide 60. This slide 60 may be moved inwardly in accordance with the position of the tool 2 and for this purpose it is shown as having the lower end portion 66 of a lever 67 bearing thereagainst. This lever is shown as fixed to an axially adjustable pivot shaft 70. In one axial position of this pivot shaft 70, as shown in Figures 2, 3, 5 and 6, the other arm 72 of the lever 67 bears with an extension 73 against the head of an abutment screw 74 threaded into the slide 11 on the opposite side of the axis of the work 5 from the tool 2. Thus as the slide is moved to bring the tool toward the work axis, the lever is rocked to press the slide 60 in the reverse direction toward the work axis, and as the slide 11 is moved outwardly the pressure of the lower end of the lever 67 is relieved so that the spring 62 may retract the slide 60 to a corresponding extent. The slides 11 and 60 are retained in their respective slideways by means of the cover plate 80 which has the slideway for the slide 31, and which may be secured to the outer face of the member 10 as by means of the screws 81. The rolls 3 and 4 may be retained in position on their re-

spective slides by means of this cover plate and as shown each one is carried by its pivot shaft in a suitable socket such as 85 in one face of its respective slide without the necessity of any means for fixing it in position. The outer edge portion of each of the rollers 3 and 4 is preferably rounded as at 86 to avoid any possibility of the work being marred thereby.

- 10 When rough work is to be turned taper the parts are adjusted as just described, the slides 31 and 60 being arranged to move with the tool toward and from the axis of the work with the tool. The tool used at this time is 15 related to the work and the work-supporting element as shown in Figure 7, having its cutting face at 90, and the work-supporting elements engaging the work back of the line of cut on the work which has been turned by 20 the tool 2, the operating traverse direction of the work being shown by the arrow A.

When it is desired to turn work tapered which has previously been turned cylindrical, the work-engaging elements may be held in 5 fixed relation to the work axis, their connections to the tool to follow the taper being rendered inoperative. For this purpose the screw 41 is retracted, as shown in Figure 4, so that it will not engage the rear end of the 20 wedge block 36 and the sleeve 55 is turned downwardly until its lower end engages the upper end of the slide 31, thus holding the slide against upward movement. The spring 50 holds the upper end of this slide against 25 the lower end of the sleeve which thus acts as a stop to limit its upward movement so that the roll 4 is held at the desired distance from the work axis to bear on the cylindrical portion thereof. The pivot shaft 70 is also ad- 30 justed from the position shown in Figures 3, 6 and 7 to the position shown in Figures 4 and 12, with a bearing portion 88 at the upper end of the lever 67 in axial alinement with an adjusting abutment screw 89 threaded into 35 the member 1. This abutment screw 89 is ad- justed so that the upper lever end bears there- on at the proper position so that the lower end of the lever presses the slide 60 inwardly to hold the roll 3 at the desired distance from 40 the work axis to bear on the cylindrical portion thereof. In this arrangement of the parts the tool 2a, as shown in Figure 8, has its cutting edge 91 substantially half way back from its forward edge so that it may cut back 45 of the engagement of the work-supporting rollers on the work, the direction of opera- tive traverse of the turner being shown by the arrows B. Thus with this adjustment of the parts the work supporting rollers are 50 held at fixed distances from the work axis and do not partake of the motion of the tool to- ward and from the axis of the work as deter- mined by the contour of the cam bar 6. The pivot shaft 70 may be retained in either of its 55 adjusted positions by means of a set screw 95

which may be engaged in either of a pair of annular grooves 96 and 97 in the pivot shaft, engagement of the set screw 95 in the groove 96 retaining the lever in position to hold the slide 60 in fixed position and engagement of the screw 95 in the groove 97 causing the lever to be held in position for the movement of the tool slide 11 to be effective in moving the work support slide 60.

Having thus described an embodiment of this invention it should be evident to those skilled in the art that various changes and modifications might be made therein without departing from its spirit or scope as defined by the appended claims.

I claim:

1. A taper turner comprising a work traversing member, a slide on said traversing member movable transversely to the direction of traverse of said member, a cam bar along which said member traverses for controlling the position of said slide, a tool carrier on said slide for holding a tool in operative relation to the work relative to the axis of which said member traverses, a work supporting device carried by said member and movable at an angle to the direction of movement of said slide, a pair of cooperating wedge elements one of which is carried by said device, means for operatively connecting or disconnecting the other of said elements to said slide, whereby movement of said slide to bring the tool toward said work causes said elements to effect the corresponding movement of said device, a spring normally pressing said device away from said axis, and an adjustable stop for limiting the extent of such movement in response to said spring.

2. A taper turner comprising a work traversing member, a slide on said traversing member movable transversely to the direction of traverse of said member, a cam bar along which said member traverses for controlling the position of said slide, a tool carrier on said slide for holding a tool in operative relation to the work relative to the axis of which said member traverses, a work supporting device carried by said member and movable toward and from the axis of the work, a lever for transmitting motion of said slide to said device, and means for supporting said lever movable to bring said lever into and out of operative position.

3. A taper turner comprising a work traversing member, a slide on said traversing member movable transversely to the direction of traverse of said member, a cam bar along which said member traverses for controlling the position of said slide, a tool carrier on said slide for holding a tool in operative relation to the work relative to the axis of which said member traverses, a work supporting device carried by said member and movable toward and from the axis of the work, a lever for transmitting motion of said slide to said de-

vice, means for supporting said lever movable to bring said lever into and out of operative position, and means for retaining said device in fixed position when said lever is out of operative position.

- 5 4. A taper turner comprising a work traversing member, a slide on said traversing member movable transversely to the direction of traverse of said member, a cam bar along which said member traverses for controlling the position of said slide, a tool carrier on said slide for holding a tool in operative relation to the work relative to the axis of which said member traverses, a work supporting device carried by said member and movable toward and from the axis of the work, a lever for transmitting motion of said slide to said device, a spring pressing said device away from the work axis and against one arm of said lever, means for supporting said lever for movement into and out of operative relation to said slide, and an adjustable stop into operative relation with which said lever end may be engaged when said lever is moved out of operative relation to said slide to define a position for said device fixed with respect to said traversing member.

10 In testimony whereof I have affixed my signature.
